KNITTING-MACHINE.

No. 805,670.

Specification of Letters Patent.

Patented Nov. 28, 1905.

Application filed November 26, 1901. Serial No. 33,736.

To all whom it may concern:

Be it known that I, JAMES E. ROWE, of Pawtucket, county of Providence, and State of Rhode Island, have invented certain new and useful Improvements in Knitting-Machines; and I do hereby declare the following specification, taken in connection with the accompanying drawings, forming a part of the same, to be a full, clear, and exact description thereof.

10 The features of the invention relate to circular-knitting machines, and may be employed with special advantage in that class of circular-knitting machines used for knitting half hose or stockings in which the needles are guided in grooves in a needle-cylinder and are acted upon by cams carried by a cam-cylinder, one of the cylinders being rotated during the formation of the leg and foot of the stocking and being reciprocated during the 20 formation of the heel or toe and the needles being thrown into and out of action automatically during the narrowing and widening on the heel and toe. In automatic machines of this class it is customary to employ sinkers 25 to hold down the loops of the fabric as the needles rise through them, and it is also usual to mount the sinkers so that they may be reciprocated, the sinkers being withdrawn to allow the needles to draw the new loops 30 through the loops upon the needles and being advanced to overlie the loops as the needles rise through them. It is also customary to employ two sets of cams located upon opposite sides of the thread-guide through which 35 the thread is led to the needles, one set of cams acting to form the wave in the needles during rotary knitting and during the movement of the cam-cylinder in the same direction in reciprocating knitting and the other set of 40 cams acting to form the wave on the opposite side of the thread-guide during the movement of the cam-cylinder in the opposite direction. With this construction one of the knitting-cams for drawing down the needles wears more 45 rapidly than the other, so that the stitches drawn by the needles in alternate courses during reciprocating knitting will be of different lengths. This inequality increases with the use of the machine and necessitates 50 the frequent renewal of the knitting-cams in order to produce an approximately even fabric on the heel and toe. In a companion ap-

plication I have shown and described a construction in which these objections are overcome by employing a single knitting-cam, 55 which forms the wave in the needles in fixed relation to the cam-cylinder, and providing means for leading the thread to the needles in front of the wave during the travel of the wave in either direction and providing sinkers which will cooperate with the needles when reciprocated by a single knitting-cam. In that construction the means for leading the thread to the needles in front of the wave comprises a thread-guide, which is 60 shifted from side to side of the knitting-cam.

One object of the present invention is to provide a more simple means for leading the thread to the needles in front of the knitting-wave, and this is accomplished by providing 70 two thread-guides located on opposite sides of the knitting-cam or knitting-wave and providing means for transferring the thread from one guide to the other.

Further features of invention relate to the 75 means for shifting the sinker-cams, so that the sinkers will be withdrawn and advanced upon the proper sides of the knitting-point as the knitting-wave travels back and forth along the active series of needles.

Further features of invention relate to the manner of mounting the sinkers, whereby the 80 lint which collects between the same is allowed to escape.

The invention also includes certain other 85 features which will be hereinafter referred to, and pointed out in the claims.

For the purpose of illustrating the various 90 features of invention a knitting-head is shown in the accompanying drawings which embodies all said features.

In the drawings, Figure 1 is a vertical sectional view of a knitting-head and so much of an automatic knitting-machine as is necessary for an understanding of the mode of operation of the head. Fig. 2 is a plan view of the latch-ring and sinker cam-ring. Fig. 3 is a detail of the means for operating the needle-controlling cams. Fig. 4 is a plan view of the cam-cylinder with the needle-cylinder removed. Fig. 5 is a horizontal sectional view through the lifting-pickers. Figs. 6 to 9 are views showing the operation of the pickers. Figs. 10 and 11 are plan views showing the

devices for operating the sinkers. Figs. 12 and 13 are views showing the manner of leading the thread to the needles. Fig. 14 is an enlarged sectional view through the centers 5 of the sinker-cams. Fig. 15 is a detail showing the manner of mounting the sinkers. Figs. 16 and 17 are details showing the devices for throwing the pickers into and out of operation. Fig. 18 is a sectional view on line 10 18 18, Fig. 4. Fig. 19 is a detail view of a guard-cam. Fig. 20 is a sectional view on line 15 20 20, Fig. 4. Figs. 21 to 24 are views showing developments of the inside of the cam-cylinder.

15 In the machine shown in the drawings the needles 1 are guided in grooves formed in the outer periphery of a needle-cylinder 2, being held in said grooves by spring-bands 3 in the usual manner. The needle-cylinder is supported by a ring 4, which may be lowered and raised to regulate the length of the stitches or for effecting the transfer of the tops of the needles by any suitable mechanism—such, for instance, as shown in Patent No. 565,218, 20 granted August 21, 1900. The needles are provided with the usual butts 5, those needles not used upon the heel and toe being provided with longer butts than the others, as is common. The cams and devices for acting 25 upon the needle-butts to give them the required movements in the operation of the machine are carried by a cam-cylinder 6, mounted to rotate upon a plate 7 and provided with a gear 8, through which the cylinder may be 30 given a continuous rotary movement or a reciprocating movement by any suitable mechanism, such as is well known in the knitting-machine art.

The needle-butts are supported upon an annular ledge 9, carried by the cam-cylinder. Between the ends of this ledge the devices for reciprocating the needles in the knitting operation and in leveling and returning the needles in transferring are located. The annular 45 ledge as well as the cams for operating upon the needle-butts are supported at some distance from the inner surface of the cam-cylinder, so that a free space is left between the cam-cylinder and the ledge and cams carried 50 thereby, through which any broken needle-butts may fall downward out of the machine. This construction also enables the pickers to be mounted inside the cam-cylinder. The ledge 9 is secured to bosses 10, projecting in 55 from the cam-cylinder, as shown in Fig. 18.

The knitting-cams for drawing down the needles and coöperating cams for raising the needles are located between the ends of the ledge 9, Fig. 21. The knitting-cam consists 60 of a plate 11, provided with converging cam-surfaces 12 and 13, which engage the needle-butts and force them downward. The coöperating cams consist of plates 14 and 15, arranged on opposite sides of the knitting-cam, 65 the plate 14 having an inclined cam-surface 16

adjacent and parallel to the cam-surface 13, and the plate 15 having a cam-surface 17 adjacent and parallel to the cam-surface 12. When the cam-cylinder rotates in the direction of the arrow, Fig. 21, the needle-butts 70 pass down the surface 12, under the point of the knitting-cam, and up the surface 16. When the cam-cylinder rotates in the opposite direction during reciprocating knitting, the needle-butts pass down surface 13, under 75 the point of the knitting-cam, and up surface 17 onto the ledge 9. Thus the knitting-cam and the coöperating lifting-cams form a wave, as shown at 18, Fig. 12, in the series of needles which travels continuously around the series of needles during rotary knitting and back and forth across the series of active needles during reciprocating knitting, the position of the wave with relation to the cam-cylinder being substantially fixed, since the lowest point of the wave is always formed by the point of the cam-plate 11. Since the needle-butts pass over the point of the same knitting-cam whenever they are drawn down to form the stitches, the stitches will be of the 80 same size throughout the fabric, and the wearing of the knitting-cam will not produce unevenness in the successive courses on the heel and toe as in the machines as heretofore constructed with two sets of knitting-cams. 85

The sinkers 19 for holding the fabric as the needles rise through the loops last drawn by them are mounted in radial grooves formed in a sinker-ring 19^a, secured to the needle-cylinder, and the forward ends of the sinkers are 90 guided in slots formed in the top of the needle-cylinder. The sinkers are provided with the usual hooks or fingers for overlying the fabric and are reciprocated in their guiding-grooves by cams carried by a sinker cam-ring 105 21, mounted to turn on the sinker-ring 19^a, the cam-ring being provided with an annular rib 22, which fits over the outer edge of the sinker-ring, and being held upon the sinker-ring by clips 23, engaging the under surface 110 of the ring, Fig. 1.

When the needles rise through the loops, there is an upward strain put upon the sinkers which tends to lift the upper edges of the sinkers above the surface of the sinker-ring, 115 where they would scrape and wear away the under surface of the sinker cam-ring as it travels over them. To avoid this wear and resulting looseness of the sinkers, a guiding-ring 20 is mounted in the inner edge of the 120 sinker-ring. The ring 20 is provided with radial grooves through which the sinkers pass and is held down in position to prevent the rise of the sinkers by the sinker cam-ring. 125

The sinker-ring is so constructed that an open space is left between the inner edge of the ring and the upper end of the needle-cylinder, and the ring is supported upon a skeleton hub through the openings 20^a, of which the lint which collects between the sinkers 130

of the preferred form of this thread-guiding means and its mode of operation will be best understood by referring to Figs. 2, 12, 13, and 15. The thread-guides 42 and 43 are formed in the latch-ring 44 and are provided with guiding edges or surfaces 45 and 46, over which the thread is drawn as it passes to the needles, the surfaces being arranged at substantially right angles to the line of travel 10 of the thread as it leads therefrom to the knitting-point, so that there is no tendency for the thread to slide laterally over said surface, Fig. 12. The two thread-guides are connected by a slot 47, which serves to direct the thread from one guide to the other, and the thread as it comes to the thread-guides passes under a guard-plate 48, secured to the outer surface of the latch-ring.

During rotary knitting the thread is led 20 over the guiding-surface 45, as shown in Fig. 12. In reciprocating knitting the thread is led over surface 45 as the cam-cylinder moves from left to right, and during the travel of the knitting-wave along the active 25 needles the thread runs to the needles in a line at right angles to the surface 45. When the knitting-cam has passed the active needles, the thread leads from the last active needle to the thread-guiding surface 45, and as the 30 thread-guide travels away from the last active needle the thread will draw over the surface 45 at an angle, as shown in Fig. 13. The angle between the thread and the surface will grow sharper as the cam-cylinder 35 continues its movement until the thread slides up the incline 45 and into the slot 47, along which it travels until it enters the guide 43, as indicated in dotted lines, Fig. 13. Now when the cam-cylinder reverses and travels 40 from right to left the thread will run through the guide 43, and when the guide has passed the inactive needles and the active needles begin to be operated by the knitting-cam the thread will run over the surface 46, as indicated in dotted lines, Fig. 12. During the 45 latter part of the stroke of the cam-cylinder in this direction the thread will slide off the incline 46 and be guided by the slot 47 into the guide 42, preparatory to the next stroke 50 of the cam-cylinder from left to right.

The latch-ring 44 is pivoted to a bracket 49, secured to the sinker-cam ring, and its vertical position is determined by a screw 50, arranged to engage the sinker-cam ring.

55 The construction and arrangement of the pickers for raising individual needles from the active series during the reciprocation of the cam-cylinder is best shown in Figs. 5 to 7, and 22 23. There are two pickers 51 and 52 60 of similar construction located upon opposite sides of the cam for reciprocating the needles. The picker 51 at the left of the knitting-cam is provided with a notched end, presenting a vertical shoulder for engagement with the 65 needle-butts, and a horizontal lip for engag-

ing the under side of the butt and lifting said butt out of the active series. The picker is mounted to slide and turn on a horizontal rod 53, located within the cam-cylinder and back of the cam-plate 11, Fig. 5. The picker is 70 forced yieldingly toward the forward end of the rod and also down upon the upper edge of the plate 15, which is recessed to receive it by a coiled spring 54, which surrounds the rod 53 and has one end secured to the support for 75 the rod and the other end secured to the picker. When the needle-butt engages the notch in the picker, the picker is forced rearwardly along the rod against the tension of the spring, and means are provided for turning the picker 80 about the rod as it is thus moved by engagement with the needle-butt, so that the lip of the picker lifts the needle-butt and transfers it to an inclined cam 55, formed on the plate 11, by which the upward movement of the needle-butt 85 into the active series is completed. In the construction shown this means consists of an inclined edge or cam 56 on the picker, which is arranged to ride over the rear edge of the plate 11, the rear side of the plate being beveled off, as indicated in Figs. 8 and 9, to properly coöperate with the inclined edge of the picker in turning the picker upward and outward as it is moved by the needle-butt. The 90 turning of the picker about the rod carries 95 the end of the picker outward until the needle-butt passes by the end of the picker, as indicated in Fig. 9, when the picker is swung downward by the spring 54 until it rests upon the tops of the needle-butts of the active series along which it rides until it has passed all of said butts and then swings down against the upper edge of the plate 15. On the return stroke of the cam-cylinder the first needle-butt in the active series after it comes up 100 105 the incline 17 strikes the back of the picker, which swings up to allow the butt to pass and rides over the butts until they have all passed, when it is swung down into the position shown in Figs. 8 and 22 ready to lift the first needle 110 115 on the next stroke of the cam-cylinder from right to left. The picker 52 is of similar construction, being provided with an inclined edge 56^a, which engages the edge of an inclined cam-surface 57 on the plate 11, and being mounted upon a rod 58 and acted upon by a spring 59. There are also two pickers 60 and 61 for depressing individual needles during the widening, which are similar in construction and mode of operation to the lifting-pickers. The picker 60 is mounted on a rod 62, carried by the cam-cylinder, and is provided with an inclined edge or cam 63, which coöperates with the edge of an inclined cam-surface 64, formed on the guard-plate 65, 120 Figs. 6, 7, and 21, and the picker 61 is mounted on a rod 66, carried by the cam-cylinder, and is provided with an inclined edge or cam 67, which coöperates with the edge of an inclined cam-surface 68 on the guard-plate 69. 125 130

may escape. This construction also enables one of the spring-bands 3 to be placed nearer the upper ends of the needles, where it will act more efficiently.

- 5 The sinkers are held in their inner position with the hooks above the fabric by an annular rib 24 on the sinker cam-ring, which passes through grooves extending laterally through the upper edges of the sinkers. The rib 24
10 has a portion constructed to form shifting or adjustable cams for reciprocating the sinkers, the points at which the sinkers are withdrawn and advanced being shifted so that the sinkers will properly coöperate with the needles when
15 operated by the single knitting-cam.

In the construction shown the sinker cam or cams are of the same construction as in the application referred to and are formed by pivoted blocks 25, 26, and 27, the blocks 25
20 and 27 being pivoted to plates 25^a and 27^a, forming parts of the rib 24, and block 26 being pivoted to the blocks 25 and 27 and forming a connecting-link between said blocks. These blocks form a part or movable section
25 of the rib 24, and they may be shifted to change the points at which the sinkers are withdrawn and advanced.

When the cam-cylinder is moving in the direction of the arrow, Fig. 12, the wave 18 is
30 traveling along the needles in the same direction, the needles on the right of the point where the loops are drawn, or the knitting-point, are moving downward, and the needles on the left of the knitting-point are moving
35 upward. When the cam-cylinder is moving in the opposite direction, the wave also travels in the opposite direction, and the needles on the left of the knitting-point will be moving down, and the needles on the right will be rising. It follows, therefore, that during
40 the movement of the cam-cylinder from left to right the sinkers should be withdrawn at the right of the knitting-point, where the needles are drawing the loops, and should be in
45 advanced position at the left of the knitting-point, where the needles are rising, and that when the cam-cylinder is moving from right to left the sinkers should be withdrawn at the left and advanced at the right of the
50 knitting-point—that is to say, the points at which the sinkers are withdrawn and advanced should be shifted from side to side of the knitting-wave as the cam-cylinder reciprocates.

55 The means employed for causing the sinker-cams to thus operate the sinkers embodies certain features of the invention and is as follows: Two pins 28 and 29 are secured to the blocks 25, 26, and 27, the pin 28 being secured concentric with the pivot between blocks 25 and 26 and pin 29 being secured concentric with the pivot between blocks 26 and 27. These pins extend up through slots in the sinker cam-ring and engage slots 30 and
60 31 in levers 32 and 33, which are pivoted to the

sinker cam-ring, Fig. 2. These levers are connected, so that when one moves outward the other is moved inward by means of a lever 34, pivoted to the sinker cam-ring at 35, the opposite ends of the lever being provided with 70 slots, which engage pins 36 and 37 on the levers 32 and 33. The levers serve to connect the sinker cam-ring to the cam-cylinder, so that the ring rotates with the cylinder, and the levers are operated through their connection with the cam-cylinder. The levers are connected with the cam-cylinder by means of a projection in the form of a shaft 41, mounted on the cam-cylinder, the upper end of which carries a roll 38, which lies between 80 and engages the outer ends of the levers 32 and 33.

When the cam-cylinder is moving from left to right, the roll 38 thrusts against the lever 33, thus holding the lever in its outward position and through it holding the blocks 25, 26, and 27 in the position shown in Fig. 10. The block 27 now acts to withdraw the sinkers at the right of the knitting-point, and the block 26 advances the sinkers at the left of 90 the knitting-point, Fig. 10. When the cam-cylinder is reversed, the roll 38 thrusts against lever 32, swinging said lever outward and lever 33 inward, thus bringing the blocks 25, 26, and 27 into the position shown in Fig. 11. 95 The block 25 now withdraws the sinkers at the left of the knitting-point, and block 26 advances the sinkers at the right of the knitting-point. Thus as the cam-cylinder reciprocates the sinker-cams are automatically 100 shifted to withdraw the sinkers in front of the knitting-point and advance them behind the knitting-point.

The action of the sinker-cams may be adjusted by means of adjustable stop-screws 39 105 and 40, carried by the levers 32 and 33 and arranged to engage the edge of the sinker-cam ring.

As the knitting-wave 18 travels along the series of needles, the thread must be led to 110 the needles in advance of the knitting-point, and since in reciprocating knitting the wave travels first in one direction and then in the other and since the wave is in fixed relation to the cam-cylinder means should be provided for leading the thread to the needles from opposite sides of the knitting-point as the cam-cylinder reciprocates. In the present construction this means comprises two thread-guides or guiding-surfaces located upon opposite sides of the knitting-cam or knitting-point and means for shifting the thread from one guide to the other, so that it is guided to the needles from the guide which is in advance of the knitting-point. The means for 115 shifting the thread from one guide to the other preferably consists of a guiding-slot connecting the two guides, by which the thread as it leaves one guide is directed into position to engage the other guide. The construction 120

The pickers 60 and 61 are held yieldingly in position to engage the butts of the inactive needles by springs 70, which hold the pickers forward against collars 72 and upward against stops 74.

On the forward stroke of the picker it acts to depress the needle-butts at the end of the inactive series and then rides under the needle-butts until they have all passed, and on the return stroke of the picker it is swung downward by the engagement of the needle-butts with the rear side of the picker and rides under the needle-butts, as indicated at 61, Fig. 23, until the butts have all passed, when it swings up into position, as indicated at 60, Fig. 23.

In the construction shown the depressing-pickers are provided with lips formed to engage and depress two adjacent needles and the lifting-pickers are continued in operation during the widening operation. The general operation of narrowing and widening is well understood and will not be described in detail.

The pickers are thrown into and out of operation by the guard-cam plates 65 and 69, which are moved at the proper times by the following devices: The guard-cam 65 is secured to a plate 76, to the rear side of which is secured a slide 77. The slide is guided in a block 78, mounted inside the cam-cylinder, Fig. 20. The plate 76 is provided with a downwardly-projecting arm 79, which engages an opening 80 in a slide 81, which is guided between the ledge 9 and cam-cylinder 6, Fig. 18. The slide 81 is provided with a radially-extending slot 82, which is engaged by a crank-pin 83, carried by a disk 84, formed on a shaft 89, which is mounted on the cam-cylinder. The guard-cam 69 is similarly mounted and connected in a similar manner to a slide 85, which is provided with a radial slot 85^a, engaged by a crank-pin 86, carried by a disk 87, which is secured on the upper end of crank-pin 83, the crank-pin 86 being diametrically opposite the crank-pin 83, Fig. 5.

During rotary knitting the parts are in the position shown in Figs. 5 and 21 with the guard-cams in their forward position against the inclined ends of the plate 11. When in this position, the guard-cams act to hold the pickers 51 and 52 back out of the path of the needle-butts. When the narrowing is to begin, the shaft 89 is given two quarter-turns, the first of which moves the guard-cams into the position shown in Fig. 23, thus releasing the lifting-pickers, and the second of which moves the guard-cams into the position shown in Fig. 22. As the cams move into this position they engage the rear sides of the depressing-pickers and turn them down out of the path of the needle-butts, as indicated. When the narrowing is completed, the shaft 89 is given a third quarter-turn, bringing the guard-cams into the position shown in Fig. 23, thus leaving both the lifting and the de-

pressing pickers free to swing into operative position. When the widening is completed, the shaft 89 is given a fourth quarter-turn, bringing the cams back into the position shown in Fig. 21. As the guard-cams move into this position the inner ends 88 of plates 76 engage the outer ends of the lifting-pickers and force them along their guiding-rods, so that they are turned upward and outward behind the guard-cams and plate 11.

The construction and arrangement of the cams for throwing the needles not used upon the heel and toe and the devices for operating these cams are novel and embody features of the invention.

The needles having long butts are thrown out of operative position at the beginning of reciprocating knitting by a cam 90, having an inclined guiding-surface 91, up which the needle-butts travel as the cam-cylinder travels from right to left. The needles that are in the idle series are thrown into operation at the end of reciprocating knitting by a cam 92, having an inclined guiding-surface 93, down which the needle-butts travel onto the ledge 9 as the cam-cylinder rotates from right to left. These cams 90 and 92 are mounted to swing radially into and out of operative position by being secured upon a lever 94, pivoted at 95, the cams being secured upon opposite sides of the pivot 95, so that when one is swung inward the other swings outward.

The lever 94 is swung about its pivot at the proper times by the movement of slide 85, the lever being connected with the slide by a pin 96, mounted in the lever and extending into a slot 97 in the slide 85.

During rotary knitting the parts are in the position shown in Fig. 16, the cam 92 being in position to engage both the long and short butts and cam 90 being out of the path of the needle-butts. When the shaft 89 is given the first two quarter-turns, the first turn brings the opposite end of the slot 97 against the pin 96 and the second quarter-turn swings the lever into the position shown in Fig. 17, thus projecting the cam 90 into position to engage the long butts and carrying the cam 92 out of the path of the needle-butts. When the shaft 89 is given its third quarter-turn, the lever is not affected, as the pin 96 rides in the slot 97; but when the shaft is given its fourth quarter-turn the lever is swung back in the position shown in Fig. 16, projecting the cam 92 into the path of both the long and short butts.

In order to enable the cams 90 and 92 to be shifted independently of the operating mechanism, the pin 96 is mounted to slide in the lever 94 and is held in position to engage the slot 97 by a spring 98. By withdrawing the pin the lever 94 may be disconnected from the operating mechanism and manually operated, and then connected with the operating mechanism, without danger of throwing the

devices out of time, since the lever 94 must be returned to the position from which it was moved before the pin 96 will engage slot 97.

The lever 94 is held in position by a spring-pressed pin 99, having a conical end engaging recesses 100.

The shaft 89 is operated at the proper times by means of a star-wheel 109, secured thereto, which is provided with four radial projections 110, arranged to engage a vertically-movable finger 111 when said finger is depressed. In case the knitting-head is used in an automatic machine the finger will be automatically moved into the path of the star-wheel just before the motion-changing mechanism is operated, so that the star-wheel will strike the finger twice while going in the same direction, thus giving the wheel two quarter-turns. The finger will then be raised until the narrowing is completed, when it will be moved into the path of the star-wheel and will be raised again after being once engaged by the wheel, which operation will be repeated at the end of the widening. The shaft is held in its different positions by spring-pressed pins 109^a, having conical ends arranged to engage recesses 110^a in the star-wheel.

The knitting-head shown is provided with means for leveling the needles when using the machine for knitting half-hose similar to the means set forth in the application referred to. The needles are leveled below the sinkers by directing the butts of all the needles into a groove or guideway 123, the major portion of which is formed by the under edge of the ledge 9 and the upper edge of a ring 124, secured inside the cam-cylinder, the space between the ledge and ring being substantially the width of the needle-butts. In order to guide the needle-butts into this groove, the plates 14, 15, and 11 and the guard-cams 65 and 69 are mounted upon a vertically-sliding block 78. The block 78 is provided with a rib 125, which fits within a guideway 126, formed in the inner surface of a curved plate 127, secured to the cam-cylinder and forming a part of its wall. The block 78 is held with the rib 125 in the guideway by a screw 128, which passes through a slot 129 in the plate 127 and has a flange 130 formed thereon, which engages a plate 131, bearing upon the outside of plate 127. The block 78 is moved vertically by means of a cam 132, secured to the shaft 41 and having a cam-groove which engages the outer end of the screw 128. The shaft 41 is mounted in a bracket 133, secured to the outer surface of the plate 127, and is provided with a handle 134, by which it may be turned. The shaft 41 is held in its normal position by a spring 135, Fig. 5, which bears upon a flat place 136 on the cam 132.

When the needle-butts are to be directed into the groove 123, the shaft 41 is turned and the cam 132 raises the block 78 until the parts

are in the position shown in Fig. 24. This brings the under sides of the plates 14 and 15 into line with the under edge of ledge 9 and brings the upper surface of a rib 137, which is secured to the block 78, into line with upper surface of ring 124, the space between the rib 137 and plates 14 and 15 forming a part of the groove for leveling the needle-butts. The cam-cylinder is then revolved in the direction of the arrow, Fig. 24, and the needle-butts on the ledge 9 pass down the inclined cam-surface 138 on the plate 15 into the guideway 123, those needle-butts which were lifted by the upward movement of the plates 14 and 15 being depressed onto the ledge 9 by the cam 95 and also passing down the incline 138. After the top has been transferred to the needles in the manner set forth in the Patent No. 565,218, referred to, the block 78 is returned to its lower position, bringing the parts into the position shown in Fig. 21. The needle-butts are returned into knitting position by a cam 139, secured to the ring 124 and arranged to project above the rib 137 and between the adjacent ends of the plates 14 and 15. As the cam-cylinder is rotated the needle-butts in the groove 123 pass down the incline 138, under the plate 15, and up the cam 139 onto the incline 16, the butts which were carried down by the depression of the plate 14 passing up a cam-surface 140 into the guideway 123.

The space between the ends of plates 14 and 15 is bridged over by a yieldingly-mounted bridge 141, which is mounted to slide radially in a recess in the block 78, Fig. 1. The bridge 141 is provided with an inclined under side 142, which bears upon the inclined upper edge of cam 139. The bridge-piece 141 is loosely mounted in its recess, so that it may have a slight vertical play, and is pressed forward by a spring 143. The bridge is held up in position by the engagement of its incline 142 with the cam 139. During the knitting the needle-butts pass over the upper surface. When the butts are forced upward by the cam 139, they strike the under side 142 and force the bridge-piece back, so that they may pass by said piece onto the cam 16.

The bridge 141 also forms a yielding cushion during the knitting for arresting the downward movement of the needle-butts and holding them up against the end of the knitting-cam. This construction enables the head to be operated at a high rate of speed and insures a uniform fabric, since the extent of the downward movement of the needle is determined by the end of the knitting-cam, and the downward movement of the needle is arrested by the cushion and not by the resistance of the loop being drawn.

For convenience in setting up the machine and in removing the parts for repair it is preferred to mount the pickers as well as the cams for guiding the needle-butts during the knitting upon the block 78 and to so mount

the block that it may be readily removed with the attached parts. This result is accomplished in the construction shown, in which the section 127 of the cam-cylinder supports 5 the block 78 and the parts attached thereto.

This section may be readily removed by removing the screws by which it is attached to the cam-cylinder.

While I have described the features of invention in connection with a knitting-head in which the knitting-wave is caused to travel about the needles by rotating the cam-cylinder, it will be understood that the travel of the wave may be produced by rotating the 15 needle-cylinder, in which case the cam-cylinder would be stationary.

What I claim as my invention, and desire to secure by Letters Patent, is—

1. In a knitting-machine the combination of 20 a circularly-arranged series of needles, a single knitting-cam for operating the needles to draw the loops during reciprocating knitting, thread-guides on opposite sides of the knitting-cam, and means for shifting the thread 25 from one guide to the other during reciprocating knitting, substantially as described.

2. In a knitting-machine the combination of 30 a needle-cylinder, needles guided therein, a cam-cylinder provided with means for forming a knitting-wave in the needles in fixed relation to the cam-cylinder during reciprocating knitting, thread-guides on opposite sides of the knitting-wave, and means for shifting the thread from one guide to the other during reciprocating knitting, substantially as described.

3. In a knitting-machine the combination of 40 a needle-cylinder, needles guided therein, a cam-cylinder provided with means for forming a knitting-wave in the needles in fixed relation to the cam-cylinder during reciprocating knitting, sinkers for holding the fabric as the needles rise, means for shifting the points at which the sinkers are advanced and withdrawn from side to side of the knitting-wave, thread-guides on opposite sides of the knitting-wave, and means for shifting the thread 45 from one guide to the other during reciprocating knitting, substantially as described.

4. In a knitting-machine, the combination, 50 with a series of needles, and means for causing a knitting-wave to travel back and forth along said series of needles, of a thread-guide on each side of the wave, and a guiding-slot 55 connecting the two thread-guides, substantially as described.

5. In a knitting-machine a thread-guide provided with a thread-engaging surface at substantially right angles to the line of the thread 60 as it passes from the guide to the needles during the knitting, a second thread-guide having a similar guiding-surface, and a slot extending from one guiding-surface to the other, substantially as described.

6. In a knitting-machine, a thread-guide 42

having an inclined guiding-surface 45, a second thread-guide 43 having an oppositely-inclined guiding-surface 46, and a slot 47 connecting said thread-guides, substantially as described.

7. In a knitting-machine, a thread-guide 42 having the inclined guiding-surface 45, the thread-guide 43 having the oppositely-inclined guiding-surface 46, the slot 47 between said guides and the guard 48, substantially as 75 described.

8. In a knitting-machine the combination of a cam-cylinder, sinkers, a sinker cam-ring provided with movable cams for operating the sinkers, and connections between the sinker-cams and cam-cylinder for shifting the sinker-cams when the cam-cylinder reverses, substantially as described.

9. In a knitting-machine the combination of a cam-cylinder, sinkers, a sinker cam-ring, 85 movable cams on the sinker cam-ring for operating the sinkers, levers pivoted on the sinker cam-ring, and connected with said sinker-cams, and a projection on the cam-cylinder engaging said levers, substantially as 90 described.

10. In a knitting-machine the combination of a sinker-ring provided with radial grooves for guiding the sinkers, sinkers guided in said grooves, a sinker cam-ring mounted on said 95 sinker-ring, a guiding-ring at the inner edge of the sinker-ring grooved for the passage of the sinkers, substantially as described.

11. In a knitting-machine the combination of a sinker-ring having radial grooves for the 100 sinkers, sinkers mounted therein, a sinker cam-ring mounted on said sinker-ring, a guiding-ring 20 at the inner edge of the sinker-ring between the sinkers and the sinker cam-ring grooved for the passage of the sinkers, 105 substantially as described.

12. In a knitting-machine the combination of cams 90 and 92 for raising and depressing the needles, a lever carrying said cams mounted on a vertical pivot, and means for rocking 110 said lever to alternately move said cams into and out of operation, substantially as described.

13. In a knitting-machine the combination of cams 90 and 92 for raising and depressing the needles, a lever carrying said cams, a reciprocating slide for operating said lever, a slot in said slide and a movable pin engaging said slot, substantially as described.

14. In a knitting-machine the combination 120 of switch-cams and depressing-pickers, means for projecting and retracting the same, connections whereby the two sets of mechanisms may be jointly and simultaneously operated, and means whereby the switch-cam-projecting 125 devices may be operated independently of said connections.

15. In a knitting-machine the combination of switch-cams and depressing-pickers, means for projecting and retracting the same, con- 130

nections whereby the two sets of mechanisms may be jointly and simultaneously operated, and means whereby one of said mechanisms may be operated independently of said connections.

16. In a knitting-machine the combination of a switch-cam, mechanism for projecting and retracting the same, pickers, connections be-

tween said mechanism and pickers for throwing the pickers into and out of operation, and means whereby the switch-cam may be projected independently of said connections.
